CLAIM

The ornamental design for a connecting adapter for endoscopic treatment tool, as shown and described.

DESCRIPTION

FIG. 1 is a top, rear and right side perspective view of a connecting adapter for endoscopic treatment tool showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a cross-sectional view thereof taken along line 8-8 of FIG. 2;

FIG. 9 is a cross-sectional view thereof taken along line 9-9 of FIG. 6;

FIG. 10 is a top, rear and right side reference perspective view showing the state in which the tip end portion of the belt is fastened to the belt fastener; and,

FIG. 11 is a top, rear and right side reference perspective view thereof in a manner of use.

The broken lines in the drawings illustrate portions of the environment of the connecting adapter for endoscopic treatment and form no part of the claimed design.
